JOHN SHELLABERGER, OF SHANE'S CROSSING, OHIO.

Letters Patent No. 80,512, dated July 28, 1868.

IMPROVEMENT IN TILE-MACHINES.

The Schedule referred to in these Letters Patent and making part of the same,

TO WHOM IT MAY CONCERN:

Be it known that I, JOHN SHELLABERGER, of Shane's Crossing, Mercer county, Ohio, have invented a certain new and useful Tile-Machine; and do hereby declare the following to be a full, clear, and exact description thereof, reference being had to the accompanying drawing, making part of this specification.

A is the box or receptacle of a pug-mill, having a shaft, B, armed with tempering-blades C, and provided with a sweep, D, having a heel or extension, D', beyond the shaft, provided with a wrist, E, connected by a pitman, F, with a vibrating-arm, G; whose lower end is connected to a rod, H, which terminates in a piston, I, that acts in its forward motion to expel the tempered clay through suitably-formed orifices J, at the bottom of one side of the chamber K beneath the box A.

The machine is intended to be propelled by horse or other animal-power, a gap, L, in the frame L permitting the passage of the team.

My machine possesses several important features of practical superiority in its construction and arrangement.

First. By forming the crank-arm by an extension, D', of the sweep D, I obviate in a great measure torsional strain upon the shaft B, which is a common cause of breakage in machines of this class as heretofore constructed.

Second. By placing the pitman F above the sweep D, and extending it in length, and the lever G, outside the path of the horses, I reduce by one-half the lateral strain upon the said lever, and thereby greatly lessen the power required to actuate it.

Third. The arrangement last named also enables me to employ a plunger-rod, H, of so great length that it requires no joint or guide, and will, by its own elasticity, accommodate itself to the curved vibration of the lever G.

Fourth. By the advantageous disposition of the parts for strength and efficiency, I am enabled to dispense with castings, and thus make my machine very cheap, simple, and easy of manufacture.

Having thus described my invention, what I claim as new, and desire to secure by Letters Patent, is—

The relative arrangement of the shaft B, sweeps D D', pitman F, lever G, and plunger H I, substantially as and for the purposes set forth.

In testimony of which invention, I hereunto set my hand.
